UNITED STATES PATENT OFFICE.

DAVID R. BOWEN, OF ANSONIA, AND CARL F. SCHNUCK, OF NEW HAVEN, CONNECTICUT, ASSIGNORS TO FARREL FOUNDRY AND MACHINE COMPANY, OF ANSONIA, CONNECTICUT, A CORPORATION OF CONNECTICUT.

MACHINE FOR TREATING RUBBER AND SIMILAR MATERIAL.

1,357,948.

Specification of Letters Patent.

Patented Nov. 9, 1920.

Application filed September 21, 1917, Serial No. 192,619. Renewed August 31, 1920. Serial No. 407,220.

To all whom it may concern:

Be it known that we, DAVID R. BOWEN and CARL F. SCHNUCK, both citizens of the United States, and the first residing in Ansonia, county of New Haven, and the second residing in New Haven, county of New Haven, State of Connecticut, have invented certain new and useful Improvements in Machines for Treating Rubber and Similar Material, of which the following is a full, clear, and exact description.

This invention relates to machines for mixing, working or masticating rubber or similar material, and it has particular reference to a machine for mixing rubber chunks of various sizes with filling or coloring material in powdered form so as to obtain a smooth resilient mass which is thoroughly homogeneous.

One of the primary objects of the present invention is the provision of a very simple, compact and economical form of mixer, in which the charging of the mixing chamber and the discharging thereof both take place at the lower part of said chamber.

Another object of our invention is to furnish a machine of the type indicated, in which the fluid pressure mechanism for actuating the pressure piston or ram is located at the top of the machine, whereas the piston or ram itself is located at the under part of the machine. Such a construction has the advantage that the piston or ram can act as a discharge controlling door as well as a charging device, while at the same time the fluid pressure actuating mechanism is readily accessible, the total height of the machine being comparatively small.

To these and other ends, the invention consists in the novel features, parts and combinations of parts to be hereinafter described and claimed.

In the accompanying drawings,

Figure 1 is a front elevation of a mixing machine embodying our improvements;

Fig. 2 is a vertical, transverse section of the machine; and

Fig. 3 is a top plan view of the upper part of the machine.

The particular machine selected for illustration comprises pedestals or end frames 5 adapted to be bolted to the floor. Between the pedestals at their upper ends is located a mixing chamber 6 approximately cylindri-

cal in shape and having journaled therein 55 a rotor 7 provided with mixing blades 8. The chamber consists primarily of an upper section 9 and a lower section 10^a, both of these sections and the rotor being preferably of hollow construction to permit the circulation of cooling fluid. The chamber carries intermediate of its ends an interiorly projecting rib 10, usually of V-shaped cross-section, which co-operates with the rotor in forming an arcuate extrusion space at the 65 intermediate portion of the cylinder through which the material is extruded alternately in opposite directions by the blades, substantially as described in our application, Serial No. 191,413. However, so far as the 70 present invention is concerned, the form of the rotor and the character of the co-operation between it and the chamber are not important, as the invention concerns itself primarily with the means for charging and 75 discharging the mixing chamber 6.

The lower chamber section 10^a has its lower portion formed as an upright cylinder 11 communicating with the working cylinder at the under portion thereof, preferably substantially throughout the length of the cylinder. The portion 11 acts as a charging and discharging cylinder for the machine, it being in this instance located perpendicularly to the working cylinder. Operating 80 in the charging and discharging cylinder is a pressure piston or ram 12, which is adapted to be raised and lowered by suitable fluid pressure mechanism located on top of the working chamber.

In the particular example shown, the piston 12 is connected at its lower end with a plate 13, to which vertical guide rods 14 are attached at the corners, said rods being vertically guided in guides 15 at the corners of the working chamber. These rods extend above the working chamber and are connected at their upper ends with a plate 14^a similar to the plate 13. The plate 14^a has a depending piston rod 15^a affixed thereto, on the lower end of which is a piston 16, working in an upright cylinder 17 mounted on top of the working chamber. The cylinder 17 is connected with a source or sources of fluid pressure by ports 18—19, suitable connections being provided for raising and lowering the piston 16 in said cylinder. When the piston 16 is raised, it carries upward 90

the pressure piston or ram 12 at the lower part of the machine through the connections described, whereby the piston 12 is raised in the cylinder 11. On the other hand, when the piston 16 occupies its lowermost position, as shown in Fig. 2, the pressure piston or ram 12 occupies its lowermost position, the greater part of the interior of cylinder 11 being then free and unobstructed.

The cylinder 11 is provided in its side wall, at what may be termed the front of the machine, with a charging and discharging opening 20. This opening is located about midway of the height of the cylinder, the arrangement being such that when the pressure piston is lowered, it will pass down beyond the lower edge of said opening. Material can then be charged into the cylinder 11 through the opening, so that it will rest on top of the piston 12, and by suitably actuating the fluid pressure piston the material can be carried upward into the working chamber 6. Before this is done, however, the charging opening must be closed to prevent the escape of material through said opening under the pressure of the piston, and for this purpose a suitable closure, such as a swinging door 21, is provided for said opening. In the particular form shown, the door 21 is hinged at one side to the body of the cylinder and at the opposite side it is adapted to be locked in the closed position by oppositely acting locking bolts 22 actuated by a hand wheel 23. It will be understood, of course, that the inner surface of the door conforms to the curvature of the piston 12, so that there will be no leakage past the piston. The latter will also preferably be provided with suitable packing as shown.

It will be observed that the upper end of the pressure piston 12 is concave in cross-section as shown in Fig. 2, thereby presenting a substantially cylindrical surface, which supplements the inner surface of cylinder 6. In other words, the cylinder 6 in conjunction with piston 12 form a substantially complete hollow cylinder. The piston 12 not only carries the material upward into the working chamber, but it holds it tightly in contact with the blades of the rotor so that the latter operate on it in a very effective way. The arrangement will preferably be such that while the upper end of the piston will move into quite close proximity to the rotating blades, it will not be possible for it to actually make contact with said blades.

When it is desired to discharge the machine, the mixing operation having been completed, the piston 12 is lowered again to the position shown in Fig. 2. The door 21 is then released and opened and the treated material is taken out of the cylinder 11.

This cylinder acts as a discharging cylinder as well as a charging cylinder because when the piston 12 is lowered, the material adhering to the rotor either falls off by gravity or is thrown off by centrifugal force, or is stripped off by the rib 10 or other suitable means, so that it falls down into the cylinder 11, the bottom of which is constituted by the piston 12.

Various changes may be made in the details of the construction without departing from the scope of our invention as defined in the claims.

We do not claim broadly herein a rubber mixing machine comprising a working chamber having an opening in the lower portion thereof, and a charging and discharging device operating in said opening, as claimed in our application Serial No. 192,030; nor do we claim herein a rubber mixer comprising a working chamber having an intermediate extrusion rib, as claimed in our application, Serial No. 191,413. Furthermore we do not claim herein the method of masticating rubber or similar material which comprises subjecting the mass to a mixing extrusion action, as claimed in our application, Serial No. 223,537.

In referring to a charging or discharging "cylinder" we employ the term in a broad sense, as it will be obvious that the cross-section of the charging device used for this purpose can be other than round without affecting the principle of the invention in any way.

What we claim is:

1. In a machine of the character described, a working chamber having an opening at the lower part thereof, a rotary mixing element in said chamber, a movable member adapted to close said opening, and power-operated means located above the working chamber for exerting pressure on said member and thereby shifting it into a position wherein it holds the material in contact with said mixing element.

2. In a machine of the character described, a mixing chamber having an opening in the lower part thereof, a rotary mixing element in said chamber, a piston in said opening to charge the material and permit the discharge thereof, and fluid pressure means located above the mixing chamber for actuating said piston.

3. In a machine of the character described, a working chamber, a second chamber communicating therewith, and a piston in said second chamber having a concave face disposed toward the interior of the working chamber.

4. In a machine of the character described, a mixing chamber having an opening in the lower part thereof, a cylinder in communication with said opening, and a piston in said cylinder having a concave upper face.

5. In a machine of the character described, a mixing chamber having an opening in the lower part thereof, a cylinder communicating with said opening, a rotor in said chamber, a piston in said cylinder having a concave face adapted to hold the material against said rotor, and means for actuating said piston.
6. In a machine of the character described, 10 a mixing chamber having an opening in its periphery, a cylinder communicating with said opening, a rotor in said chamber, and a piston in said cylinder having a curved face to hold the material in contact with said rotor.
7. In a rubber mixing machine of the single cylinder type, a mixing cylinder having an opening in its periphery, a second cylinder communicating with the first by 20 way of said opening and arranged radially with respect to said mixing cylinder, a rotor in said mixing cylinder, and a piston in said second cylinder for holding the material in contact with said rotor, said piston having 25 its face conforming generally to the curvature of said mixing cylinder.
8. In a rubber working machine, a working chamber, a pressure piston beneath the same, and actuating means for said piston located above said working chamber.
9. In a rubber mixing machine, a working chamber, a rotor therein, an upwardly moving pressure piston in the lower part of the chamber, and a fluid pressure piston and cylinder for actuating said first piston, located above said working chamber.
10. In a rubber mixer, a working chamber, a pressure piston, arranged transversely thereto and adapted to be moved into proximity to the periphery of said chamber, and operating means for said pressure piston located at an opposite point in the chamber periphery.
11. In a rubber mixer, a working chamber, and means including a fluid pressure device arranged above the working chamber for carrying upward into the chamber a batch of material located beneath the same.
12. In a rubber mixer, a working chamber, means beneath said chamber for carrying upward into the same a batch of material located below said chamber, and means located above said working chamber for operating said carrying means.
13. In a rubber mixing machine, a working chamber, a cylinder and piston for feeding the material into said chamber in a generally upward direction, and an actuating cylinder and piston for said first piston located at the opposite side of the working chamber.
14. In a rubber mixing machine, a working chamber, a cylinder and piston for feeding the material into said chamber in a generally upward direction, and an actuating cylinder and piston for said first piston supported on top of the working chamber.
15. A rubber mixing machine having a pressure piston or ram shaped to conform to and supplement the conformation of the main mixing chamber in which the rotor is located, substantially as described.
16. A rubber mixing machine, having a pressure piston arranged transversely to the working chamber in which the rotor is located, and adapted to be moved into proximity to the periphery of the rotor, said pressure piston being shaped to conform to and to supplement the conformation of the working chamber, suitable operating means being provided for said pressure piston at the opposite side of the chamber.

In witness whereof we have hereunto set our hands on the 18th day of September, 1917.

DAVID R. BOWEN.
CARL F. SCHNUCK.
